INSERT HAVING INTERNAL DRIVE GROOVES
José Rosán, San Juan Capistrano, Calif., assignor to
Rosan Engineering Corp., Newport Beach, Calif., a
corporation of California

Filed Dec. 4, 1961, Ser. No. 157,327

5 Claims. (Cl. 85—45)

This application is a continuation-in-part of application Serial No. 640,470, filed February 15, 1957, which, in turn, is a continuation-in-part of application Serial No. 618,594, filed October 26, 1956, both of which are now abandoned.

This invention relates to inserts adapted to be installed in an opening in a work piece and characterized by the incorporation of an externally threaded wall and an internally threaded bore.

Driving such inserts into the work piece opening has constituted a major problem in the successful utilization thereof. Typical expedients utilized in prior art constructions have included the incorporation of polygonal drive openings at one extremity of the internally threaded bore, or the formation of polygonal drives through the length of the internal bore.

I have found that it is possible to drive such inserts much more effectively by the provision of drive groove means in the wall of the internal bore. The drive groove means is formed in the bore wall and intersects the successive convolutions of the internal thread to define chordal arcs or arcuate thread segments in said internal thread.

Because of the provision of drive groove means of the character incorporated in inserts of the invention, it is possible to maintain the integrity of the internal thread of the insert, thus providing for adequate thread engagement between the internal thread of the insert and a fastener disposed therein. Moreover, the drive groove means, being interposed between the chordal arcs of the internal thread, provides driving sides or faces which may be engaged by a tool having driving protuberances whose configuration conforms substantially to the configuration of the drive groove means, thus insuring that driving torque is equally distributed throughout the length of the insert.

Moreover, as will be described in greater detail below, the formation of the drive groove means with their bases or bottoms disposed inwardly of the major diameter of the internal thread results in maintenance of the structural integrity of the internal thread with the consequent hoop strength achieved thereby. Thus, positive driving engagement with the drive groove means not attainable by prior art polygonal drives which do not offer the advantages of the increased strength in the hoop, is achieved. Furthermore, application of the driving force to the driving faces of the drive groove means at an angle such as to employ the full columnar strength of the drive groove means permits the application of substantially greater driving force without distortion of the cylindrical character of the insert as would occur in prior art polygonally formed devices.

The drive groove means of the invention can be provided in a variety of configurations and it is not intended that the teachings of the invention be limited to any particular configuration. For instance, I have utilized angularly configured grooves, rectangular grooves, semi-circular grooves and the like. However, to preserve the integrity of the internal thread, it is essential that the bottom of the groove means, regardless of its shape, be located inwardly of the root of the internal thread to preserve the integrity of said internal thread for reasons and results to be adverted to hereinbelow in greater detail. Penetration of the wall of the insert beyond the thread

2

root will seriously interfere with the wall strength. In any event, the depth of the groove means should always be less than the depth of the thread.

Obviously, the number of drive grooves utilized will depend upon many factors; the torque imposed during driving; whether the insert is self-tapping, and the like. Therefore, I do not desire the concept of my invention to be limited to the incorporation of any particular number of grooves. In addition, the arrangement of the drive grooves can be symmetrical or assymmetrical.

Among the many advantages accruing from an insert incorporating the teachings of my invention is an extremely positive drive with the drive load extending the entire length of the insert. Moreover, the nature of the drive tool is such that the chordal arcs of the threads are effectively cleared by the drive tool, resulting in unimpaired integrity of the thread.

Of particular importance is the fact that the drive groove means is so related to the successive convolutions of the internal thread as to provide for a continuum through said successive convolutions. In other words, because the drive groove means are of less depth than the depth of the tread, the root thereof is unimpaired and integral. Thus, the hoop strength of the successive convolutions of the internal thread is preserved, and the intermediate chordal arcs of the thread convolutions constituted by successive arcuate thread segments thus achieve a short columnar effect tending to resist displacement or distortion when the drive tool is inserted in the groove means to drive the insert into the work piece bore.

Therefore, there is no tendency for the walls of the groove means to deflect away from the engaging portions of the drive tool, and a uniform linear contact is established along the length of the drive tool. The linear uniform contact results in even drive load distribution with consequent elimination of points of stress concentration during the driving of the insert.

Because of the maintenance of the structural integrity of the successive convolutions of the internal thread and the consequent preservation of the hoop strength of said successive convolutions, repeated removal and installation of the insert from and into the bore in the work piece is feasible. This process is implemented by the shape of the drive groove means of the invention, which permits facile insertion and removal of the drive tool into the drive groove means of the internal bore of the insert.

The depth of the driving groove means in either the four or six drive groove embodiment relative to the radius depth of the internal thread major diameter may vary from 25% to 90% depending upon the diameter of the internal thread, the type of thread, the type and/or functional purpose of the insert, that is, whether it is plain or self tapping, the material in which the insert is to be mounted, and the like.

It is essential for a complete understanding of the teachings of the invention that the concept of the drive groove means be visualized with accuracy. Initially, as will be described in greater detail below, the drive groove means are formed in the cylindrical wall of the internal bore, and subsequently, the internal thread is formed in said bore with the root of said thread disposed outwardly of the bottom of the groove means. After the thread has been formed in the previously broached wall of the internal bore, each longitudinally oriented groove means is constituted by a successive series of aligned grooves formed in the successive convolutions of the internal thread. In essence, the individual grooves formed in the successive convolutions may be considered minor grooves which, together, constitute the major longitudinal drive groove of the invention.

I have found that the drive groove means of the invention is particularly applicable to inserts characterized by extremely thin walls. In utilizing the teachings of the invention in thin wall inserts, it is of utmost importance that the drive groove or grooves be characterized by the elimination of sharp angles at the bases thereof which would constitute stress concentration lines. Therefore, even in triangularly broached, or otherwise formed grooves, the apex of the triangle will be an included radius.

Typical of the application of the teachings of my invention is the provision of drive grooves in a thin wall insert with the grooves arranged in a pattern which might be considered to be coincident with the included angles of a square or hexagon. Of course, such a description is by way of analogy only since even when the grooves are of angular configuration they are not polygonally included angles generated by planar surfaces but, rather, grooves generated in the internal bore while still maintaining the structural integrity of the thread in three ways; namely:

- (1) By not permitting the groove depth to equal that of the thread;
- (2) By preserving the chordal arcs of the thread intermediate the drive groove or grooves;
- (3) By not permitting lines of stress concentration to be created in the thread by the incorporation of sharp included angles in the bases of the grooves.

Other objects and advantages in the invention will be apparent from the following specification and the accompanying drawings, which are for the purpose of illustration only and in which:

FIG. 1 is a top plan view of an insert constituting one embodiment of the present invention with the groove means thereof arranged in a four point pattern;

FIG. 2 is a side sectional view of the insert of FIG. 1;

FIG. 3 is a side view of the insert of FIGS. 1 and 2 showing the fastener being driven into a work piece bore, shown in section, by a drive tool adapted to engage the groove means of the insert;

FIG. 4 is a vertical sectional view of another embodiment of the invention installed in a work piece;

FIG. 5 is a vertical sectional view of yet another embodiment of the invention;

FIG. 6 is a top plan view of another embodiment of the invention showing the groove means thereof arranged in a modified octagonal pattern;

FIG. 7 is a top plan view showing another embodiment of the invention incorporating a single, rectangularly formed groove means;

FIG. 8 is a top plan view of yet another embodiment of the invention illustrating the utilization of two angularly shaped groove means;

FIG. 9 is a vertical, partly sectional view illustrating the formation of the groove means in the wall of the internal bore of an insert having six driving grooves, before tapping;

FIG. 10 is a vertical sectional view on an enlarged scale of a portion of the insert of FIG. 9, taken as indicated by line 10—10 in FIG. 11 after tapping, illustrating the form of the internal thread in the previously grooved wall of the bore;

FIG. 11 is a bottom plan view showing the engagement of the broach of FIG. 9 with the wall of the internal bore;

FIG. 12 is an enlarged, fragmentary top plan view illustrating the configuration of the successive convolutions of the internal thread with the drive groove means formed therein;

FIG. 13 is a vertical partially sectional view on an enlarged scale similar to the embodiment of FIG. 1 of the drawings;

FIG. 14 is a vertical sectional view illustrating the broaching of the longitudinal groove means in the wall of the internal bore;

FIG. 15 is a bottom plan view illustrating the engagement of a 4-point drive tool with the corresponding groove means of the insert of FIGS. 1, 2, and 13 of the drawings; the tool being shown fragmentarily;

FIG. 16 is a schematic view illustrating the relationship of the cutting edges of the broach and the portions of said broach intermediate said cutting edges, respectively, with the internal thread root and the contiguous chordal arcs intermediate the groove means; taken from the bottom as shown by line 16—16 of FIG. 14;

FIG. 17 is a diagrammatic view illustrating a typical driving tool for an insert of the character of FIGS. 1 and 13;

FIG. 18 is a diagrammatic view illustrating a typical driving tool for an insert of the character of FIG. 10;

FIG. 19 is an enlarged fragmentary sectional view illustrating particularly the relationship between the drive groove means and the corresponding thread convolutions;

FIG. 20 is a top plan view on an enlarged scale of the insert FIG. 7 prior to the formation of the threads in the internal bore by tapping;

FIG. 21 is a diagrammatic view of a drive tool adapted for utilization with the insert of FIG. 7;

FIG. 22 is a diagrammatic view illustrating a driving tool adapted for utilization in conjunction with the insert of FIG. 8;

FIG. 23 is a fragmentary view, to an enlarged scale, showing additional details of the construction of a modified form of the drive groove of the insert.

Referring to the drawings, and more particularly to FIGS. 1-3, I show an insert 10 which may be of the self-tapping insert type, said insert having a cylindrical body incorporating a bore 11 having an internal thread 12. Incorporated in the peripheral exterior wall of the insert 10 is an external thread 13 having a slotted self-tapping end formation 14. The successive convolutions of the internal thread 12 incorporate a plurality of longitudinally extending drive groove means 15 which, in the instant case, are four in number.

A setting tool 16 of substantially square cross section adapted for utilization in conjunction with the insert 10 is mounted in a chuck 17 of a power tool and, as best shown in FIGS. 1-3, the tool 16 will interfit and engage with the drive groove means 15 of the insert 10 so that the insert may be rotated in and cut threads in the bore 18 of a work piece 19.

After the insert 10 has been installed in the bore 18, the tool 16 can be readily withdrawn from operative engagement therewith. Facile installation and withdrawal of the drive tool into and from operative engagement with the corresponding drive groove means of the invention is one of the desirable characteristics of the invention which will be adverted to in greater detail hereinbelow.

In the modification of the invention shown in FIG. 4, a fastener element 20 has an externally threaded portion 21 for insertion in the threaded bore 22 of a work piece 23 and has a locating pin extension portion 24 adapted to extend into an aperture in a complementary work piece 25 to be secured to work piece 23. The locating pin portion 24 is formed with a threaded bore 26, the threads of which are interrupted to form longitudinally extending grooves 27 adapted to be engaged by a seating tool similar to tool 16 having a corresponding number of radial enlargements capable of engaging grooves 27. FIG. 4 shows a cap screw 28 to be run in the bore 26 for securing work piece 25 in contact with work piece 23.

In FIG. 5 is shown another modified form of the invention. In this figure a self-tapping insert or fastener 30 has a slotted and beveled end 30a and self-tapping threads 31 for seating in a bore 32 of a work piece 33 and has a threaded bore 34 formed with a plurality, in this case six, of longitudinal grooves 35 similar to grooves 15 and 27 for the same seating purpose.

The longitudinal grooves in the bore of the fasteners may be of any desired number or shape. The fastener

36 of FIG. 6 has internal threads 37 and longitudinal grooves 38 which are eight in number and equally spaced circumferentially. The fastener 40 of FIG. 7 has internal threads 41 and a single groove 42 which may be rectangular in shape and adapted to be engaged by the rib of a seating tool. The fastener 43 of FIG. 8 has internal threads 44 formed with a pair of grooves 45 which are angularly shaped with radial faces to be engaged by a similarly shaped seating tool.

A preferred method of fabricating the drive groove means of an insert 50, which said drive groove means arranged in a pattern of six drive grooves, is illustrated in FIG. 9 of the drawings. The insert 50 has been provided with an external thread 52 adapted to engage a correspondingly threaded bore, not shown, in the work piece, and drive groove means 54 have been formed in the wall of the bore 56 by a broach 60 incorporating a pilot 62 and a plurality of broaching points or lines 64 whose configuration corresponds to the desired ultimate configuration of the drive groove means 54.

The broaching operation is illustrated in FIG. 11 of the drawings and it will be noted, at this juncture, that the drive groove means 54 formed in the wall of the bore 56 are angularly configured but are characterized by the incorporation of radii at the base thereof. The incorporation of radii at the bases of the drive groove means 54 prevents the creation of lines of stress concentration, which, particularly in the case of thin wall inserts might result in failure thereof; these radii are designated by the reference number 54A throughout.

After the formation of the drive groove means 54 in the above-described manner, the wall of the bore 56 of the insert 50 is provided with an internal thread 70 which, as best shown in FIG. 10 of the drawings, is characterized by the fact that the major diameter of the thread root is disposed outwardly of the longitudinally extending groove means 54, as set forth dimensionally in tables appearing hereinbelow. In other words, the bottoms of the groove means 54 are disposed intermediate the major and minor diameters of the internal thread 70.

During the broaching process when the longitudinally oriented drive groove means 54 are formed in the above-described manner, the portions 74 of the broach 60 intermediate the cutting points 64 leave the wall of the bore intermediate the drive groove means 54 undisturbed. Therefore, when the internal thread 70 is cut in the wall of the internal bore 56, arcuate threaded segments constituting chordal arcs are formed in said wall to provide the successive convolutions of the internal thread 70 with thread segments of unimpaired integrity.

Thus, when a drive tool 80, such as that shown in FIG. 18 of the drawings, is utilized in driving the insert 50 into a work piece, not shown, it will be provided with successive engagement points 82 arranged in a six drive groove pattern corresponding to the six drive groove pattern of the drive groove means 54 of the insert 50, and the areas 84 of said drive tool intermediate said points will clear the chordal thread segments intermediate the drive groove means 54.

The relationship of the drive groove means 54 with the associated chordal thread segments is graphically illustrated in FIG. 12 of the drawings wherein the internal thread 70 is illustrated as incorporating a plurality of chordal segments 90 which are interposed between the drive groove means 54 and which are characterized by the presentation of unimpaired cooperating surfaces to the correspondingly formed male convolutions on a fastener inserted into the internal bore 56 of the insert 50.

Also illustrated in FIGS. 10 and 12 of the drawings is the manner in which the bottoms or bases of the drive groove means 54 are disposed intermediate the major and minor diameters of the internal thread 70, thus providing a continuity of structural thread integrity which resists axial and torsional displacement of the chordal arc segments 90 of the internal thread 70 because of

the hoop strength of the residual thread. The resistance to such displacement correspondingly enhances the columnar strength of the longitudinally extending drive groove means 54.

Another aspect of the invention graphically illustrated in FIGS. 10 and 12 of the drawings is the radial configuration of the bottoms or bases of the drive groove means 54. As a primary matter, it should be explained that the inserts 50 of the invention are found in a large range of sizes and that in the smaller sizes, the radial configuration of the bases or bottoms of the groove means 54 may not be readily perceptible to the naked eye. However, the radii are always present at the bases or bottoms of the drive groove means 54 and prevent the creation of linear stress concentrations which might result in the structural failure of the insert 50. In considering the drive groove means 54, it will be noted that after the internal thread 70 has been formed in the wall of the bore 56, the drive groove means 54 are constituted by a series of vertically aligned recesses 92 which, in essence, constitute minor groove means which serve cooperatively to define the longitudinally extending major groove means 54 of the invention.

The typical dimensions of a thin wall insert 50 incorporating 6 drive groove means 54 are set forth hereinbelow in inches. The insert incorporates a $\#7/16$ -20 internal thread and a $\#1/2$ -20 external thread.

A =External major diameter, .500
 B =External pitch diameter, .4675
 C =External minor diameter, .4620
 D =Internal minor diameter, .390
 E =Internal pitch diameter, .409
 F =Internal major diameter, .448
 G =The single depth of the internal thread is .029.
 H =The depth of the internal thread remaining between the bases of the drive groove means 54 and the major diameter of said thread is .0069.
 I =Internal groove radius, .2140 (as indicated in FIG. 12 of the drawings).
 J =Angle of radiused groove=approximately 120° included.

The percentage of the radial depth of the internal thread occupied by the drive groove means is 33.5%.

Another embodiment 110 of the insert of the invention is illustrated in FIG. 13 as constituted by a cylindrical body 112 having an external thread 114 formed thereupon. The body 112 incorporates a bore 116 which is provided with a plurality of the drive groove means 118.

The drive groove means 118 are arranged in a four drive groove pattern. The drive groove means 118 are located intermediate chordal arc thread segments 119 whose terminal extremities are located adjacent the drive groove means 118.

In fabricating the insert 110 the external thread 114 is formed upon the external wall of the body 112. Subsequently, as shown in FIG. 14, a broach 130 having a pilot 132 and four successive symmetrically arranged sets of successive cutting points or lines 134, 134', 134'' . . . , is introduced into the bore 116. In this manner, the elongated, longitudinally extending drive groove means 118 are formed in the wall of the bore 116 prior to the fabrication of the internal thread 120, and preferably parallel to the bore axis.

After the formation of the drive groove means 118 in the above-described manner, the internal thread 120 is formed in the bore by tapping said thread therein. The thread root is disposed outwardly of the bases or bottoms of the drive groove means 118, as best shown in FIG. 13 of the drawings, said bases or bottoms being located intermediate the major and minor diameters of said thread and insuring structural continuity of said thread throughout all of the convolutions thereof.

The relationship of the broach 130 with the ultimately formed internal thread 120 is schematically illustrated

in FIG. 16 of the drawings, wherein the cutting points 134 of said broach are illustrated as being disposed intermediate the major and minor diameters 140 and 142, respectively, of said thread. Moreover, the manner in which the portions 144 of the broach 130 intermediate the cutting points 134 clear the contiguous areas of the wall of the bore 116 intermediate the drive groove means 118 is also illustrated in FIG. 16 of the drawings.

A typical driving tool 150 having four driving points 152 is illustrated in FIG. 17 of the drawings and shown engaged with the corresponding drive groove means 118 in FIG. 15 of the drawings. It will be noted that, as in the case of the broach 130, the portions of the driving tool 150 intermediate the driving points 152 clear the chordal arc thread segments of the internal thread 120 to prevent damage to the thread segments during the driving operation.

The dimensions of a typical insert 110 incorporating four drive groove means are set forth hereinbelow in inches. The insert incorporates a #6-32 internal thread and a #10-32 external thread.

A'=External major diameter, .190

B'=External pitch diameter, .169

C'=External minor diameter, .161

D'=Internal minor diameter, .115

E'=Internal pitch diameter, .119

F'=Internal major diameter, .145

G'=The single depth of the internal thread is .015.

H'=The depth of internal thread remaining between the bases of the drive groove means 118 and the major diameter of said thread is .0091.

I'=Internal groove radius, .0635 (as indicated in FIG. 15 of the drawings).

J'=Angle of radiused groove=approximately 120° included.

The percentage of the radial depth of the internal thread occupied by the drive groove means is 60%.

The dimensional tables presented hereinabove constitute a basis for determining the amount of material left between the major diameter of the internal thread and the bases of the drive groove means. It should be understood that in all cases the base of the drive groove means is always disposed internally of the major diameter of the thread to provide the requisite thread strength in the areas thereof underlying the drive groove means. The amount of material remaining between the major diameter of the internal thread and the base of the drive groove means will naturally vary with the pitch, type and size of the internal thread utilized.

I have found that an effective range of drive groove means depth lies within a range of 25% to 90% of the height of the internal thread where said height is determined by the dimension between the internal thread major and minor diameters. As stated hereinabove, the particular percentage of thread height which the drive groove means consumes is a criterion of the specific type of internal thread utilized. The percentage of the radial depth of the internal thread occupied by the drive groove means is obtained by taking the difference between the internal major diameter *F* and twice the depth of the internal groove radius *I*, and dividing it by the difference between the internal major diameter *F* and the internal minor diameter *D*.

For example, in the case of the #7/16-20 internal and #5/8-20 external thread insert, described in the tabulation in column 6, *F* is given as .448, *I* as .214, and *D* as .390.

$$F-2I=.448-2 \times .214=.020$$

$$F-D=.448-.390=.058$$

To obtain the percentage of the radial depth of the internal thread occupied by the drive groove means, we divide *F-2I* by *F-D* and multiply by 100.

$$\frac{.020}{.058} \times 100 = 33.5\%$$

For the #7/16 internal and #10/16 external, as described in the tabulation above, *F*=.145; *I*=.0635, and *D*=.115, so that

$$F-2I=.145-2 \times .0635=.018$$

$$F-D=.145-.115=.030$$

10 In percentages this becomes:

$$\frac{.018}{.030} \times 100 = 60\%$$

The relationship between the various structural components of the insert 50 is shown in greatly enlarged fragmentary cross-section in FIG. 19 of the drawings. Particularly illustrated in FIG. 19 is the manner in which the major diameter portion of the internal thread 70 constitutes an unbroken continuum underlying the groove means 54 to achieve the requisite structural integrity, thus imparting the desired columnar effect to the drive groove means 54. Perceptible also is the radius 54A provided at the base of the groove means 54 to prevent the creation of stress concentration lines which would cause ultimate failure of the insert 50.

25 The consequent hoop strength of the successive convolutions of the internal thread 70 resists deflection of the longitudinally oriented drive groove means 54 during the driving or removal of the insert 50. Moreover, the structural integrity of the internal thread 70 considerably rigidifies the chordal arc thread segments 90, which lie between adjacent drive groove means 54, axially and torsionally.

The insert 40 of FIG. 7 of the drawings is illustrated in FIG. 20 after the formation of the rectangular groove 42 therein by a broaching operation similar to those described hereinabove. Of course, the thread 41 is subsequently formed in the bore of the insert 40. A drive tool 170 is shown in FIG. 21 as having a cylindrical body 172 and a radial key or protuberance 174 adapted to engage in the corresponding drive groove means 42.

40 A drive tool 180 adapted to be utilized in driving the insert of FIG. 8 into a work piece bore is illustrated in FIG. 22 of the drawings. The drive tool 180 includes a cylindrical body 182 having radial protuberances 184 adapted to be inserted in the corresponding drive groove means 45 of the insert 43.

45 It will be observed that in the embodiments, such as that of FIG. 8 and the corresponding tool of FIG. 22, the more acute the angle between the ends of the adjacent chordal segments, the greater the resistance to the columnar loading imposed by engagement with a tool having corresponding radial protuberance configurations. This avoids distorting the cylindrical shape of the insert when force is exerted by a driving tool. The same principle may be applied to the driving groove of the inserts shown in the other figures.

An alternative embodiment 50' of the insert of the invention is disclosed in enlarged fragmentary form in 50 FIG. 23 of the drawings as incorporating drive groove means 54' of slightly different configuration from the drive groove means 54 of the insert 50. The drive groove means 54' of the insert 50' is characterized by the incorporation of a broader base which, in turn, incorporates a plurality of radii 54A, the adjacent chordal thread segment being indicated at 90°.

55 As previously disclosed, the drive groove means of the invention may be formed in any configuration including semi-circular. However, where the drive groove means is formed to incorporate an included angle, the degree of angularity of the walls of the groove constituted by the extremities of the chordal arcs is determined by such factors as the torque necessary to install the insert, the pitch of the external threads, the depth of the external threads and the like. However, it should be noted that

in order to provide for driving engagement with the driving tool, the walls of the drive groove means must be disposed at such an angle as to transmit the driving force into the chordal arc segments of the internal thread in such a direction that the tendency to distort the insert wall outwardly will be minimized. The direction in which the driving force is applied should be as nearly as possible tangent to the insert wall adjacent the point of application of the driving force.

Therefore, the various embodiments of the insert of the invention described hereinabove are characterized by certain salient and significant structural features which include the provision of longitudinally extending drive groove means in the bore of the insert, said drive groove means having their bases located intermediate the major and minor diameters of the internal thread of said bore; the preservation of the structural integrity of the internal thread by the retention of the major diameter portions of the root of the thread in underlying relationship with the drive groove means; the provision of drive groove means of a variety of configurations as determined by an end view thereof; the symmetrical disposition of the drive groove means in the wall of the bore or, conversely, the asymmetrical distribution thereof; and the provision of thread portions or chordal arc thread segments of unimpaired integrity which afford columnar strength during rotation of the insert for either insertion or removal, these columnar portions providing for strengthened engagement with a correspondingly threaded male element.

As a consequence of the incorporation of the salient features of construction set forth hereinabove, an insert having drive characteristics unobtainable with prior art constructions is achieved. Repeated insertion and removal of the insert is feasible because of the elimination of distortion or deflection of the drive groove means by maintaining the structural integrity of the internal thread major diameter portion.

Furthermore, repeated removal of the associated male fastener from the bore of the insert is feasible because of the fact that the chordal arc thread segments of said internal thread are not impaired when the insert is removed or driven into the bore in the work piece. This is attributable to the fact that the driving torque is imposed upon chordal arc segments strong enough to sustain the applied torque. Thus, frequent removal and/or installation of the insert leaves the segments of the internal thread in unimpaired condition for the reception of a corresponding male fastener.

I claim:

1. An insert adapted to be installed in a workpiece having a bore, comprising: an elongated cylindrical body having an external thread for mounting said insert within said bore in said workpiece, said body having a bore incorporating an internal thread, and having a thin wall between said internal and external threads, all of said internal threads being load-carrying threads engageable by a threaded member entering through the upper extremity of said body, said internal threads being con-

stituted by a plurality of successive convolutions having major and minor diameters, and a plurality of longitudinal drive grooves extending across all of said internal threads and being engageable by a driving tool through said upper extremity of said body for driving said body into said workpiece, said drive grooves having their bases located inwardly of said major diameter and outwardly of said minor diameter of said internal threads, whereby said drive grooves do not extend into and weaken the wall between said internal and external threads, the limited depth of said drive grooves leaving unimpaired circumferentially continuous major diameter thread portions disposed radially outwardly of said drive grooves, whereby the structural integrity of the major diameter portions of the successive convolutions of the internal threads is maintained, said drive grooves occupying a minor portion of the circumferential length of any given convolution of said internal threads, thereby forming chordal arc segments in said successive convolutions, the terminal portions of said segments being triangular and being formed by the side walls of said drive grooves, said drive grooves providing means through which high torque can be applied in driving said insert without causing any substantial reduction in the strength of said internal threads to resist axial stripping when a threaded member is tightened therein.

2. An insert as defined in claim 1, wherein the depth of the drive grooves is about 25% to 90% of the radial dimension of said internal threads.

3. An insert as defined in claim 1, wherein the drive grooves are V-shaped and the sides thereof are disposed on an angle of about 120°, and wherein the bottom of the drive grooves is rounded.

4. An insert as defined in claim 1, wherein the depth of the drive grooves is about 25% to 90% of the radial dimension of said internal threads, and wherein the drive grooves are V-shaped and the sides thereof are disposed on an angle of about 120°, and wherein the bottom of the drive grooves is rounded.

5. An insert as defined in claim 1, wherein the external thread is a self-tapping thread, and wherein the lower extremity of the body is provided with slots that decrease in depth in a direction toward the upper extremity of said body.
